LUBRICATOR

Charles E. Stewart, Verdun, Quebec, Canada,
assignor to Juno Corporation, Ltd., Montreal,
Quebec, Canada

Application August 20, 1934, Serial No. 740,563

6 Claims. (Cl. 184—29)

The present invention relates to oil lubricators of the force feed type.

An object of the invention is the provision of a lubricator designed to feed lubricant to reciprocating parts of a mechanism in accordance with the operating speed thereof.

A further object of the invention is the provision of a lubricator designed so that the lubricant fed to a reciprocating member will vary in proportion to the variation in the movement of the said member.

Another object of the invention is the provision of lubricating apparatus having operating means adapted to be connected with and driven by the fluid pressure of reciprocating mechanism to be lubricated by the apparatus.

A still further object of the invention is the provision of a force feed lubricator operable by piston actuated means for automatically lubricating mechanism embodying reciprocating elements.

Still another object of the invention is the provision of a lubricator of the above character which is compact and durable in construction and reliable in operation.

Other objects and advantages of the invention will become apparent as the description progresses.

In the accompanying drawings forming a part of this specification and in which like reference characters are employed to designate corresponding parts throughout the same:—

Figure 1 is a side elevational view of a conventional type of air pump showing the lubricating apparatus operatively connected therewith,

Figure 2 is a top plan view of the lubricator,

Figure 3 is a transverse section on the line 3—3 of Figure 2, showing the piston in one position,

Figure 4 is a similar view showing the piston in a reverse position,

Figure 5 is a vertical transverse section through the lubricant reservoir,

Figure 6 is a similar view showing the eccentric in a different adjustment, and

Figure 7 is a longitudinal section through the lubricator illustrating a plural oil chamber assembly.

Referring to the drawings, wherein for the purpose of illustration is shown a preferred embodiment of the invention, the numeral 10 generally designates a vertically elongated chamber having a movable cover 11 and constituting an oil reservoir.

The chamber 10 provides for bearings in its

opposite side walls. On one wall is an opening to receive a bearing, on the opposite wall is an opening through a projecting bearing. Perforated caps screw on the inside bearing and a terminal cap on the outside bearing. A plurality of chambers 10 can thus be connected as shown in Figure 7.

At one side of the chamber 10 is mounted a cylinder 12 having ports 13 at each end for connection with fluid conduits. Within the cylinder 12 is mounted a reciprocating piston 15 embodying a pair of spaced complementary disc sections 16 rigidly joined by a centrally disposed connecting bar 17. The lower edge of the bar is formed with teeth 18 constituting a toothed rack.

A rotary drive shaft 20 extends through the bearings of the walls of the oil chamber 10 and through a recess in the bottom portion of the cylinder 12. Loosely mounted on the shaft 20 within the cylinder is a gear wheel 21 formed with teeth 22 on a portion of its periphery to form a segmental gear meshing with the toothed rack 18. Keyed upon the shaft 20 at one side of the gear wheel 21 is a ratchet wheel 23 formed with peripheral ratchet teeth engaged by a pawl 24 pivotally connected at one side of the gear wheel 21. A spring 25 attached to the pawl and bearing against the pin on the gear wheel is disposed to resiliently urge the pawl into engagement with the teeth of the ratchet wheel.

On that portion of the shaft 20 projecting through the oil chamber 10 is a driving cam 27. This cam is composed of an inner eccentric 28 keyed to the shaft 20 and an outer eccentric 29 adjustably mounted on the inner eccentric 28 and secured thereto by the set screw 34.

By means of these eccentrics 28 and 29 the eccentricity of the cam 27 may be varied from zero to a maximum as shown in Figure 5. An intermediate adjustment is shown in Figure 6. The cam 27 is disposed within and vertically reciprocates an elongated eccentric frame 30 formed with an upwardly projecting guide bar 31 at the top and a downwardly extending plunger 32 at the bottom. The guide bar 31 slides in a groove in a guide frame 33 mounted in the upper portion of the oil chamber.

The plunger 32 is slidably fitted in and functions as a force in a pump cylinder 35 in the bottom of the chamber, the cylinder having communication with an outlet 36 projecting through and outwardly of the chamber bottom. Within the cylinder 35 and outlet 36 are mounted spring check valves 37 and 38 providing inlet and discharge control means so that the plunger in con-

junction with the cylinder form a force pump for ejecting the oil from the chamber.

When the lubricator is connected with mechanism embodying reciprocating elements, as for example with an air pump or compressor as shown at Figure 1, a pair of pipes or conduits 40 connect the end outlets 13 of the lubricator cylinder 12 with a cylinder of the air pump. A lubricator duct 41 connected with the outlet 36 10 of the oil force pump is directed from one or more of the oil chambers to the lubricating connections on the compressor.

During operation of the compressor the fluid pressure of the cylinder with which the lubricator 15 is connected functions to reciprocate the lubricator piston 15 in synchronism with or simultaneously with the movement of the compressor piston. As the piston 15 moves in the direction shown by the arrow at Figure 3, it rotates the gear wheel 21 in one direction, without effecting movement of the ratchet. When the piston slides in a reverse direction it rotates the gear wheel in reverse movement at the same time rotating the ratchet wheel 23 due to the engagement of the pawl 24 therewith and effects an operative movement of the shaft 20. The rotary movement of the shaft 20 through simultaneous rotation of the eccentric 27 will cause vertical sliding movement of the pump plunger 32 within the pump cylinder. It will thus be noted that only alternative strokes of the piston 15 actuate the ratchet and the shaft by which the ratchet is keyed so that the operation of the piston imparts an intermittent movement to the shaft and, through the eccentric mechanism, to the pump plunger 32.

By this operation the oil contained in the chamber or reservoir 10 is automatically fed through the feed pipe 41 to the reciprocating 40 parts of the compressor. It will also be observed that the piston 15 will be operated at a speed corresponding to the operative speed of the compressor piston and that oil will be supplied to the compressor directly in accordance with the speed 45 of the moving parts. The pressure in the force pump structure of the lubricator may be varied by adjusting the complementary eccentrics 28 and 29 enabling variation in the stroke of the plunger.

As particularly shown in Figure 7, the apparatus 50 may embody one or any desirable number of oil reservoirs so that different parts of reciprocating mechanism may be lubricated and various types of lubricant may be fed thereto. In such case, different parts of an engine or other mechanism may be lubricated from a single lubricating unit, and, although the piston will be actuated in synchronism with the piston of the engine to which the apparatus is connected, the oil feed from the various chambers may be varied by adjustment of the operating eccentrics.

While the lubricator has been shown and described in connection with an air compressor it is readily apparent that it is adaptable for use in conjunction with many other types of mechanism, as for instance marine and stationary engines, stokers and the like.

It is to be understood that the form of my invention herein shown and described is to be tak-

en as a preferred example of the same, and that various changes as to the shape, size and arrangement of parts may be resorted to without departing from the spirit of the invention or the scope of the subjoined claims.

Having thus described my invention, I claim:

1. A lubricator comprising an oil chamber, a cylinder, a drive shaft extending through the oil chamber and cylinder, a force feed pump in the chamber driven through the medium of the drive shaft and an adjustable cam, a piston operatively mounted in the cylinder, and means operable by the piston for driving the shaft.

2. A lubricator comprising an oil chamber, a cylinder, a drive shaft extending through the oil chamber and cylinder, a force feed pump in the chamber driven through the medium of the drive shaft and an adjustable cam, a piston operatively mounted in the cylinder, and means operable by the piston for intermittently driving the shaft.

3. A lubricator comprising an oil chamber, a cylinder, a drive shaft extending through the oil chamber and cylinder, a force feed pump in the chamber driven through the medium of the drive shaft and an adjustable cam, a piston operatively mounted in the cylinder, and gear and ratchet means operable by the piston for driving the shaft.

4. A lubricator comprising an oil chamber, a cylinder, a drive shaft extending through the oil chamber and cylinder, a force feed pump in the chamber driven through the medium of the drive shaft and an adjustable cam, a piston operatively mounted in the cylinder, and gear and ratchet means in the cylinder operable by the piston for intermittently rotating the shaft.

5. A lubricator comprising an oil chamber with parallel sides with central bearings, a cylinder secured to the chamber and having a recess in its lower portion, transverse bearings in each side wall of the recess, said transverse bearings being co-axial with the chamber bearings, a drive shaft extending through said central and transverse bearings, a force feed pump in the chamber having a plunger with a yoke, an adjustable cam on the drive shaft operating in the yoke to vary the quantity of oil discharged by the plunger, a piston in the cylinder, means to reciprocate the piston, and means operable by the piston for rotating the drive shaft intermittently.

6. A lubricator comprising a plurality of oil chambers with parallel sides, having bearings therein adapted to connect the adjoining chambers, a cylinder secured to the end chamber, said cylinder having a recess in its lower portion, said recess having transverse bearings in its walls, co-axial with the chamber bearings, a drive shaft journaled in these bearings, a force feed pump in each chamber each having a plunger with a yoke, adjustable cams on the drive shaft one operating in each yoke to vary the quantity of oil discharged by the plungers, a piston in the cylinder, means to reciprocate the piston, and means in the cylinder operated by the piston to rotate the drive shaft by intermittent steps.

CHARLES E. STEWART.
